(57) **CLAIM**

The ornamental design for a pad for gripping objects, as shown and described.

DESCRIPTION

FIG. 1 is an isometric view of a pad for gripping objects showing our new design.

FIG. 2 is a front view thereof.

FIG. 3 is a back view thereof.

FIG. 4 is a top view thereof.

FIG. 5 is a bottom view thereof.

FIG. 6 is a left side view thereof; and,

FIG. 7 is a right side view thereof.

The shade lines in the Figures show contour and do not claim surface ornamentation or treatment.
